UNITED STATES PATENT OFFICE.

ADOLPH ST. ANDREWS, OF MANVILLE, RHODE ISLAND.

PICKER-CHECK FOR LOOMS.

SPECIFICATION forming part of Letters Patent No. 706,270, dated August 5, 1902.

Application filed January 2, 1902. Serial No. 88,178. (No model.)

To all whom it may concern:

Be it known that I, ADOLPH ST. ANDREWS, a citizen of the United States, residing at Manville, in the county of Providence and State 5 of Rhode Island, have invented a new and useful Improvement in Picker-Checks for Looms, of which the following is a specification.

This invention relates to picker-checks for looms used to check and arrest the picker. • when the shuttle is thrown from the shuttle-box.

The object of the invention is to more effectually check the picker and control the throw of the shuttle.

15 The invention consists in the peculiar and novel construction of the picker-check, more fully set forth hereinafter.

To throw a shuttle fairly across the warp without injury to the filling carried in the 20 shuttle, it should be started easily without a blow and moved with increasing velocity. When the highest speed is attained, the picker by which the shuttle is thrown should be checked and gradually arrested. To secure 25 these results, I provide the shuttle-box with a tube closed at the outer end. In this tube I place a piston, to the outer end of which I secure the picker-check, which is perforated and slides on the picker-rod. A tensile 30 spring is connected with the picker-check and the end of the shuttle-box.

Figure 1 is a longitudinal sectional view of a loom provided with my improved picker-check. Fig. 2 is a rear view of the shuttle-box and part of the lay of a loom, showing the picker and picker-check in the position 35 before the shuttle is thrown in solid lines and after the shuttle is thrown in broken lines. Fig. 3 is a sectional view of the piston and 40 tube, forming the support of the picker-check and the air-cushion. Fig. 4 is a view of the face of the picker-check, the picker-rod and the piston-rod being shown in section.

In the drawings, A indicates the loom-frame, 45 B the lay, C C the shuttle-boxes, D the picker-sticks, E the sweeps, and F the heel-springs.

a indicates the picker which slides on the picker-rod a' and extends through a slot into the shuttle-box, being operated by the picker- 50 stick.

The parts so far described form the usual shuttle-throwing mechanism for looms.

In carrying out my invention I secure to

the shuttle-box by means of the brackets a² and a³ the tube a⁴, open at the end toward 55 the center of the loom and closed at the outer end. I provide this tube, near the closed end, with an escape-opening a⁵. Into the tube a⁴ I insert the piston-rod a⁶, which fits the tube with a sliding fit. The bracket a⁷ is secured 60 to the screw-threaded end of the piston-rod a⁶. It is provided with the eye a⁸, to which one end of the spiral tensile spring a⁹ is secured, the other end of the spring being secured to the arm a¹⁰ on the bracket a³. A cushion a¹¹, 65 of leather or other suitable material, is placed on the flat face of the bracket a⁷ and covered by the metal plate a¹², which is secured to the bracket by the bolt a¹³. The bracket, the cushion, and the plate a¹² are perforated, so as 70 to slide on the picker-rod a'.

I find in practice that by the use of this device the shuttle is more uniformly thrown from one shuttle-box into the other, that there are less breaks of the filling-thread, and that 75 the check is far more durable than picker-checks as heretofore used.

Having thus described my invention, I claim as new and desire to secure by Letters Patent—

1. In a picker-check for looms, the combination with a tube and a piston-rod sliding in the tube, of a bracket secured to the piston-rod and having its face provided with a cushion, a metal plate covering the face of the 85 cushion, and the tensile spring secured to the bracket and a fixed part of the loom near the end of the shuttle-box, as described.

2. In a picker-check for looms, the combination with the shuttle-box, the picker, and 90 the picker-rod, of the tube a⁴ closed at one end, the opening a⁵ near the closed end of the tube, and the brackets a² and a³, of the piston-rod a⁶, the bracket a⁷ secured to the piston-rod, the cushion a¹¹, the plate a¹² secured 95 to the bracket by the bolt a¹³, and the tensile spring a⁹ secured to the bracket and a fixed part of the loom, as described.

In testimony whereof I have signed my name to this specification in the presence of 100 two subscribing witnesses.

ADOLPH X ST. ANDREWS.
